(57) **CLAIM**

The ornamental design for an exercise cycle frame, as shown and described.

DESCRIPTION

FIG. 1 is a perspective view of the exercise cycle frame of the instant invention;

FIG. 2 is a left side elevational view thereof;

FIG. 3 is a right side elevational view thereof;

FIG. 4 is a front view thereof;

FIG. 5 is a rear view thereof;

FIG. 6 is a top view thereof; and,

FIG. 7 is a bottom view thereof.

The broken lines are for the purpose of illustrating portions of the article that form no part of the claim.
